(57) **CLAIM**

The ornamental design for a bar table, as shown and described.

DESCRIPTION

FIG. 1 is a perspective view of a bar table showing my new design.

FIG. 2 is a front view of a bar table thereof.

FIG. 3 is a rear view of a bar table thereof.

FIG. 4 is a left side view of a bar table thereof.

FIG. 5 is a right side view of a bar table thereof.

FIG. 6 is a top view of a bar table thereof.

FIG. 7 is a bottom view of a bar table thereof.

FIG. 8 is a perspective view of a bar table showing an alternate position of use of my new design.

FIG. 9 is a front view of a bar table thereof.

FIG. 10 is a rear view of a bar table thereof.

FIG. 11 is a left side view of a bar table thereof.

FIG. 12 is a right side view of a bar table thereof.

FIG. 13 is a top view of a bar table thereof; and,

FIG. 14 is a bottom view of a bar table thereof.

The broken lines in the drawings depict portions of the bar table that form no part of the claimed design.
